CLAIM

The ornamental design for a lighting attachment device, as shown and described.

DESCRIPTION

FIG. 1 is a front perspective view of one embodiment of a lighting attachment device;

FIG. 2 is a back perspective view of the lighting attachment device of FIG. 1;

FIG. 3 is a symmetrical side view of the lighting attachment device of FIG. 1;

FIG. 4 is a symmetrical front view of the lighting attachment device of FIG. 1;

FIG. 5 is a top view of the lighting attachment device of FIG. 1;

FIG. 6 is a bottom view of the lighting attachment device of FIG. 1;

FIG. 7 is an open view of the lighting attachment device of FIG. 1 in use; and,

FIG. 8 is a closed view of the lighting attachment device of FIG. 1 in use.
